Primary Examiner — Marianne Pandozzi(74) *Attorney, Agent, or Firm* — Norton Rose Fulbright Canada LLP(57) **CLAIM**

The ornamental design for a beverage dispenser, as shown and described.

DESCRIPTION

FIG. 1 is a perspective view of a beverage dispenser showing the design;

FIG. 2 is a front view of the beverage dispenser in FIG. 1, FIG. 3 is a rear view of the beverage dispenser in FIG. 1; FIG. 4 is a left side view of the beverage dispenser in FIG. 1;

FIG. 5 is a right side view of the beverage dispenser in FIG. 1;

FIG. 6 is a top plan view of the beverage dispenser in FIG. 1; and,

FIG. 7 is a bottom plan view of the beverage dispenser in FIG. 1.

The broken lines in the drawing depict portions of the beverage dispenser that form no part of the claimed design.
